CLAIM

The ornamental design for a biological sample collector device, as shown and described.

DESCRIPTION

FIG. 1 is a front perspective view of a biological sample collector device showing our new design;

FIG. 2 is a rear perspective view thereof;

FIG. 3 is a right side view thereof, the left side view being a mirror image;

FIG. 4 is a top view thereof;

FIG. 5 is a bottom view thereof;

FIG. 6 is a front view thereof; and,

FIG. 7 is a rear view thereof.
